(57) **CLAIM**

I claim the ornamental design for a rearview device, as shown and described.

DESCRIPTION

FIG. 1 is a front perspective view of the rearview device of the present disclosure;

FIG. 2 is a front elevational view of the rearview device of FIG. 1;

FIG. 3 is a side elevational view of the rearview device of FIG. 1;

FIG. 4 is a top plan view of the rearview device of FIG. 1; and,

FIG. 5 is a bottom plan view of the rearview device of FIG. 1.

The broken lines shown in FIGS. 1-5 represent unclaimed portions of the article and form no part of the claimed design.
